UNITED STATES PATENT OFFICE.

CARL W. SWANSON, OF CHICAGO, ILLINOIS.

POWER-DRIVEN WASHING-MACHINE.

1,300,203.

Specification of Letters Patent.

Patented Apr. 8, 1919.

Original application filed July 27, 1917, Serial No. 183,027. Divided and this application filed March 8, 1918. Serial No. 221,214.

To all whom it may concern:

Be it known that I, CARL W. SWANSON, a citizen of the United States, residing at Chicago, in the county of Cook and State of Illinois, have invented certain new and useful Improvements in Power-Driven Washing-Machines, of which the following is a specification.

This invention relates to improvements in power driven washing machines and more particularly to driving means, latching means and other mechanisms associated with the tub and a manually operable means for simultaneously controlling said mechanisms. One of the particular objects of the invention is to provide improved means for shifting the power from the tub-oscillating mechanism and for simultaneously locking the tub in fixed position by the instrumentality operable as a result of movement of the manually moved lever.

Another object is to so construct the gearing and its associated controlling apparatus so as to avoid accidents and to insure its easy and proper action by an unskilled operator.

Still another object is to provide a control device by means of which the tub, which in the embodiment illustrated, is of the oscillating type, may be locked in any of a number of selected positions, after its oscillating mechanism has been disconnected from the source of power.

Other objects of my invention are to generally improve and facilitate the ease and positiveness of operation of machines of this character.

Still other and further objects will become readily apparent, to persons skilled in the art, from a consideration of the specification when taken in conjunction with the drawings, wherein:

Figure 1 is a side elevation of a washing machine embodying my invention.

Fig. 2 is a horizontal section, taken on line 2—2 of Fig. 1.

Fig. 3 is an enlarged section of the tub locking mechanism, taken on line 3—3 of Fig. 1, showing the tub locked in position, and

Fig. 4 is a similar view showing the tub unlocked.

In all the views the same reference characters are employed to indicate similar parts. The machine illustrated in the drawings

is an oscillating type, power driven washing machine, with permanently attached wringer driving mechanism, and in certain respects the present application is a continuation of my application which resulted in Patent No. 1,247,175 dated November 20th, 1917, entitled Washing machines. And, furthermore, this is a divisional application from my copending application Serial No. 183,027 filed July 27th, 1917.

In general features the apparatus comprises a pair of spaced-apart vertical frame members between which is pivoted an oscillatable tub, driven by an electric motor. The motor is connected through a suitable speed reducing gearing to a horizontal shaft, from which the tub and wringer are driven. The mechanisms for oscillating the tub and for controlling the wringer are not shown in detail, in the present application, as the same is completely illustrated and described, as well as claimed in my copending application and patent above referred to.

Mounted on the upper end portion of the frame, at one side of the wringer, which receives its power through the reversible gearing connected to a vertically disposed shaft, the lower end of which, in turn, receives power from one end of the horizontal shaft, previously referred to. At a convenient place, near the outer end of the wringer, a lever is positioned for controlling the wringer-driving gearing and by means of which the rotation of the wringer rolls can be stopped, started or reversed. The wringer and its driving gears are rotatable about the vertical shaft so that it can be swung in a horizontal plane from a position over the top to either side thereof. Another control lever, conveniently located near the front of the frame, operates a clutch in the tub driving mechanism and releases a latch for holding the tub stationary in a selected position.

Referring now more in detail to an embodiment of the invention disclosed in the drawings, the numeral 10 indicates in general the left, and 11, the right vertical frame on which the entire mechanism is supported. Each frame member comprises vertical corner posts 12, 13, connected at the top and bottom by cross bars 14, 15. An additional cross piece 16 extends between the posts, slightly above the bottom bar 15 and the post 17 extends downwardly from the top

- bar 14 near its center and merges into two diverging legs 18 and 19, connected to the front and back posts 12 and 13, respectively. A hub 20 is provided at the juncture of the 5 post 17 with legs 18 and 19 and serves as a bearing for the stub shaft upon which the tub oscillates. Cross members 22-22 connect the side frames, forming a rigid structure.
- 10 The mechanisms receive their power from the horizontal shaft 23 which extends across the lower part of the frame. Rotatably and slidably mounted upon the shaft 23 is a gear wheel 24, which meshes with an elongated 15 pinion 25, carried on the inner end of a short shaft 26 that is journaled in a hub 27 carried by the frame. A pulley 28 connected to the outer end of the shaft 26 is driven by the belt 29, from the small pulley 30 on the 20 electric motor 31. The motor is mounted upon a bracket 32 secured to the front of the frame, and receives its current through wires 34, leading from the switch 35, conveniently located on the post 12, and from 25 which extends the wires 36, carrying at their ends a connecting plug 37 for insertion in an electric light fitting, or socket.
- 30 A crank arm 38 is carried on the right end of the shaft 23 and through the medium of a link 39 oscillates the tub as the shaft rotates. This portion of the apparatus, as well as others, relating more particularly to the tub drive, are fully illustrated and described in the application to which reference 35 has been made above.
- 40 An A shaped extension 40 projects upwardly from the top bar 14 of the frame 10 and carries at its apex a vertical hub 41 on which the wringer, indicated in general, at 42, is mounted. Since the wringer, and the apparatus for driving it, forms no part of this application, particular description thereof will be omitted.
- 45 The wringer driving shaft 51 extends vertically up the outer side of the frame 10 and is journaled at its upper end inside the tubular wringer post 43 and at its lower end in a bearing 52 carried on the cross member 16.
- 50 The mechanism for driving the wringer from the shaft 51 is contained in the casing 83. The vertical shaft 51 carries at its lower end a beveled gear wheel 91 meshing with the beveled gear 92 on the hub 93, loosely 55 mounted on the shaft 23. The sliding gear wheel 24 carries at opposite ends of the hub, clutch teeth 94, 95, for engagement, respectively, with the wringer driving hub 93 and a collar 96 secured to the shaft 23 and 60 through which the tub oscillating mechanism is actuated. The clutch member 94 is always in engagement with the wringer driving hub, irrespective of whether the gear 24 has been slid along pinion 25 to throw the 65 clutch end 95 into engagement with the hub

96 or is in neutral position and disconnected from the tub. The wringer shaft 51 is therefore in constant rotation whenever the motor is being operated and the wringer rolls are controlled entirely by the lever 87 operating 70 on the mechanism contained in the casing 83.

For the purpose of moving the sliding gear 24 I have provided an annular groove 97 on its hub, for engagement by a fork arm 98. The forked arm is secured on the end of the shaft or rod 99, axially slidable through a journal 100 on the end frame 10. A control rod 101 extends vertically up the outer side of the frame 10, being journaled in the hub 102, 103 on the frame. The lower end 80 of the rod 101 carries an arm 104 with a forked end 105 engaging a pin 106 in the outer end of rod 99. Rotation of the rod 101 through the medium of the arm 104, slides rod 99, consequently moving gear 24 into or 85 out of tub driving position. The upper end of the rod 101 carries a forked head 107, in which is secured, on a horizontal pin 108, an end of the operating lever 109. The free end of the lever 109 terminates in the handle 110 90 and passes through a pair of yokes 111, 112, the former of which is rigidly secured to the top bar 14 of the frame and the other of which is pivoted near its right hand end on a horizontal pin 113, carried by the yoke 111. 95 The right hand end—looking at Fig. 4—of the yoke 112, carries a latch 114 arranged for engagement with the notches 115 on the quadrant 116 carried by the tub 21. The left end of the yoke 112, being the heavier, the 100 latch end normally tends, by effect of gravity, to ride up into engagement with one of the notches in the quadrant to lock the tub in selected position. The yoke 111, it will be noted, has in its bottom arm, an upstanding projection 117 so that when the lever 109 is in the position shown in Fig. 3, the tub driving clutch, then being out of engagement, the outer end of the yoke 112 is free to drop, throwing its inner latch end up into engagement with the notch in the quadrant 116 on the tub.

To start the tub in operation, the handle 110 is raised, thus throwing the latch out from engagement with the quadrant, and having been raised high enough to clear the stop 117, it can then be swung to the left, rotating the rod 101 and moving the gear 24 into tub driving position. The lever 109 can then be dropped against the lower leg of the yoke 111, which is somewhat higher than the part of said leg, to the right of the stop 117, and the pivoted yoke 112 will be held in elevated position with its latch out of engagement with the quadrant, as shown in Fig. 4. 115 The hand lever 110, which is conveniently located at the front of the machine, cannot be horizontally moved to the right into clutch engaging position as it must first be raised to clear the stop 117. In perform- 120 125 130

ing the reverse operation, it will be apparent that the tub driving clutch cannot be thrown into engagement without first disengaging the tub lock.

5 Whereas I have illustrated and described but a single embodiment of my invention, it will be evident, to those skilled in the art, that various changes and modifications may be made therein, without departing from 10 the spirit of the invention and within the scope of the appended claims.

Having described my invention, what I claim is:—

1. The combination with a washing machine frame, of an oscillatable tub; a source of power for oscillating the tub; a clutch between the source of power and the tub; a latch for engagement with the tub to lock it in selected position, and a lever having a 20 compound movement and connected to the clutch for operation thereof when moved in one part of its compound movement in one direction and to the latch to cause operation thereof, when moved in another part of its 25 compound movement in another direction.

2. The combination with a washing machine frame, of an oscillatable tub; a source of power for oscillating the tub; a clutch between the source of power and the tub; a 30 latch for engagement with the tub to lock it in selected position, and a lever having a compound movement and connected to the clutch for operation thereof when moved in one part of its compound movement in 35 one direction and to the latch for operation thereof, when moved in another part of its compound movement in another direction, and means to prevent the lever from moving it more than one operative direction at one 40 time.

3. The combination with a washing machine frame, of an oscillatable tub mounted

thereon; a source of power, for oscillating the tub; automatically operable latch, normally in engagement with the tub to lock it in selected positions and a lever connected to a clutch member and movable to start operation of the tub and coincidentally to displace the latch to release the tube.

4. The combination with a washing machine frame, of an oscillatable tub mounted thereon; a source of power, for oscillating the tub; a gravity operated latch, normally in engagement with the tub to lock it in selected positions and a lever connected to a clutch member and movable vertically to unlatch the tub and laterally to start it in operation.

5. The combination with a washing machine frame, of an oscillatable tub mounted thereon; a source of power, for oscillating the tub; a gravity operated latch, normally in engagement with the tub to lock it in selected position; a lever connected to a clutch member and movable vertically to release the latch and laterally to start operation of the tub and means to prevent return of the lever to normal position by lateral movement thereof.

6. The combination with a washing machine frame of an oscillatable tub; driving means for oscillating the tub; a latch automatically operable for engagement to lock the tub to the frame, and a lever connected to a clutch member and movable in one direction to connect the clutch members and displace the latch, and movable in the opposite direction to disconnect the clutch members and permit the latch to move into position to hold the tub locked to the frame.

In testimony whereof I hereunto set my hand.

CARL W. SWANSON.
